FRANK KOEWING, OF WEST ORANGE, NEW JERSEY, ASSIGNOR TO KOEWING PATTERNS, INC., OF NEW YORK, N. Y., A CORPORATION OF NEW YORK.

PATTERN FOR GARMENTS.

1,419,634.

Specification of Letters Patent. Patented June 13, 1922.

Application filed June 14, 1919. Serial No. 304,338.

To all whom it may concern:

Be it known that I, FRANK KOEWING, a citizen of the United States of America, residing at West Orange, county of Essex, 5 State of New Jersey, have invented certain new and useful Improvements in Patterns for Garments, of which the following is a specification.

My invention relates to paper patterns for 10 garments and comprises an improved process of making such patterns and the product of such process.

The preferred form of my invention and 15 an example of the best embodiment thereof at present known to me is illustrated in the accompanying two sheets of drawing in which—

Fig. 1 is a plan view of part of a complete 20 pattern cut along the broken line 1, and Fig. 1^a is a similar view of the remainder of the pattern cut along the broken line 7^a.

The patterns are preferably printed on, 25 and then cut from, a continuous roll of paper, Y, in continuous rotation, by a cylinder press, of indefinite length and variable width, to meet requirements. Each complete pattern, when printed and cut from the roll is folded, put in envelopes, and is then ready for sale.

30 The paper is to be made with integral, or printed, longitudinal lines provided with some pointed devices, such as arrows, pointing in one direction, Z, interchanging with a separate simple design such as a flower Z' 35 pointing in the opposite direction—these lines being parallel to the marginal edges of the roll of paper, alternating with other parallel, but continuous, plain lines X, or with any other equivalent arrangement. The

40 purpose of the arrows Z is to point in the downward direction in which the nap, if there be any in the material of which the garment is to be made, is to run in every part of the garment when cut and assembled, 45 while the flower design Z' is to point in the upward direction in which the figure design element, if there be any in the material, is to run throughout the whole garment symmetrically and concurrently when completed.

50 The purpose of the alternating, continuous lines X is to parallel the lengthwise threads, or warp, of the material, so that when the pattern is laid upon the goods in such manner as to secure the alignment of 55 the continuous lines in the pattern with the

lengthwise threads in the material, the arrows point downward with the nap and the flowers pointing upward to correspond with any figure design running in one direction on the material, it being understood that in 60 standard practice such figure design on cloth points in a direction opposite that in which the nap runs. This will assure that said features in all parts, when the latter are assembled to form the garment, shall run 65 substantially parallel and harmoniously throughout the completed garment.

Each complete pattern part contains, in addition to the longitudinal arrows Z, and flower design Z', and alternating parallel 70 lengthwise lines X, printed outlines of the various parts of the garment, serially numbered; also, on every pattern part, the catalogue number, size, and name of garment, seam and outlet seam lines, waist-line, plaits 75 and other details with their respective names as shown in the drawing, as well as a card of instructions for the proper construction of each garment part and joining adjacent parts thereto. Of course, the parallel lines 80 X, could be omitted and the arrows or other marks relied on to show direction of warp threads.

The outlines of the various garment sections (parts 1, 2, etc.) are arranged on the 85 plate for printing on the paper in such manner as to leave as little waste space as possible consistent with the functioning of the arrow and flower design, as well as the parallel, longitudinal, lengthwise lines to correspond with the stated features and lines of the material as shown in the drawing.

Obviously the parallel warp lines, nap and figure-design marks, might be printed at the 95 same time that the pattern outlines are printed, but I prefer the method first above suggested of having these first mentioned lines and marks, which may be called the textile features, made integral with the paper by watermarking, as it contrasts them 100 from the pattern outlines, and renders both clearer to the user's eye.

Matching, or joining, marks V shaped, with a letter within the V, illustrated in the drawing (A, B, C, and so on) are printed 105 on the pattern parts, each lettered V having a duplicate or mate, in some other part of the pattern. These are featured adjacent to the exterior or outer lines of the various pattern parts, denoting the points which 110

must be registered, or matched when the parts are assembled to form the garment. At each matching mark is also shown the number of the part containing the corresponding duplicate letter, as an additional convenience and aid in locating the proper pattern part.

Seam lines and outlet seam lines are printed and designated by name, as well as such other helpful details as waist-lines, plaits, etc., as shown in the drawing; likewise there is provided at all curved outlet seam lines, a series of short dotted lines, *l, l*, running at right angles from or substantially normal to the outer edge of the pattern part to the outlet seam line showing where the pattern may be cut and folded back to the seam line to facilitate said seam line being marked on the material, (as by pinning, penciling, threading, or chalking) without injuring the pattern part, so that it may be used again on the underlying, duplicate piece of goods.

The edge of the pattern sheet which is to be applied to the folded edge of the doubled material has this information printed thereon, the same method being followed as to the selvedge, as shown in the drawing.

The card of instructions, printed on, and applying to each part, is of particular advantage to the user of the pattern, for by this means the instructions are placed where most convenient and can be condensed into a few terse, easily comprehended sentences. Everything aiding in the construction of the garment being thus provided on the different pattern parts where it is most handy, all is made so clear that the merest novice will find the otherwise complicated task of cutting and making up a garment from the pattern made easy and mistakes practically impossible.

The complete pattern being printed on a sheet of paper or similar material, hundreds of thousands of copies can be rapidly produced at slight cost for each pattern.

When the purchaser uses the pattern she can instantly lay the entire sheet accurately on a piece of goods folded lengthwise of corresponding width and length, (thereby avoiding the task of arranging the various parts one by one, on the goods) and by cutting both the pattern and material at one operation, along the exterior or outer lines of the several parts, produce duplicate garment sections which, when assembled and fitted will form a perfect garment. This can be done without technical knowledge and with the least labor and waste of material. The sheet should be firmly pinned to the material within the seam lines of each part (1, 2, etc.) before cutting so that the pattern parts, when cut, will adhere to, and stay in position on the duplicate sections of material, and the matching marks (A, B, etc.),

and outlet seam lines can thereafter be transferred to the goods by pinning, penciling, threading or chalking before assembling the garment sections for basting, fitting and sewing.

In case a garment of different length from the pattern is desired, those parts containing a length-adjustment line marked "waist-line" on the drawing, may be cut along that line, then spread apart, or overlapped, a distance sufficient to produce the desired variation in length. A similar provision is made for lengthening or shortening sleeve portions, and is shown in the drawing, consisting of the words "elbow 70 line" and associated marks.

In case the goods to be used are of different width than that of the pattern sheet, or if the user prefers, for any reason to do so, as for instance, when making the garment 75 from material that has already done service as a garment of another shape or kind, the pattern parts are to be first cut out, the separate parts being then arranged and pinned, in the ordinary way, on such new, or previously used goods. In such event the advantages of the guiding parallel, longitudinal lines for application to the lengthwise thread, the arrows for the nap, or the flower design for the figure or design elements of 80 the material, as well as the lettered matching marks and other features described above will be as potent aids and safe guards as in the other procedure.

I am aware that it has heretofore been 100 proposed to mark on pattern parts lines indicating the lengthwise or warp threads, but this was done after the outlines of the pattern parts had been marked on plain paper, those of each part, regardless of the direction 105 of the lengthwise lines of the other parts, as they happened to lie, arranged most economically as to space occupied. The result was that the several parts could not be placed in alignment on the garment material until 110 after they were cut from the sheet. Such procedure was so impracticable and costly as to make it commercially useless. By first providing, as I do, paper containing the longitudinal lines, and adjusting the pattern 115 parts to these lines, instead of adjusting the lines to the parts, I eliminate the separate marking of these lines and reduce the cost of producing the patterns to a minimum.

Having described my invention, I claim as 120 new:

1. The process of forming printed patterns for garments, which comprises preparing a sheet of paper containing a series of longitudinal lines, parallel to the marginal edges of the paper on which said patterns are to be printed and also printing on said paper the outlines of the various parts of the pattern so arranged that when the pattern is laid upon the cloth with the longi- 125 130

tudinal lines parallel to the warp threads of the cloth and the cloth cut along the pattern outlines, the warp threads of all the parts will be substantially parallel one to another 5 when the parts are assembled to form a garment.

2. A garment pattern having a direction guide marked thereon indicating the direction corresponding to that in which any nap 10 on the material should run in every part when the parts are joined to form the garment.

3. A garment pattern having a direction guide marked thereon indicating the direction corresponding to that in which any un-invertible figure design in the material 15 should run in every part when the parts are joined to form the garment.

4. A pattern for garments comprising a sheet of material having the various outlined parts of the garment marked and numbered thereon, each numbered part also having marginal joining marks adapted to register with identical marks on another part when 25 the parts are properly assembled to form a garment, each pair of marks designed to so register being marked with identical distinguishing characters, and the mark on each member of each pair being numbered to correspond to the number of the part bearing the mark with which it is to register.

5. The process of forming assembled, printed patterns for garments which com-

prises preparing a sheet of paper containing a series of longitudinal lines, parallel to 35 the marginal edges thereof, said lines being adapted to be placed parallel to the warp thread of the cloth or material, and also printing on said paper the outlines of the various parts of the pattern, so arranged and 40 assembled in accurate position relative to the said longitudinal lines that when the pattern sheet is laid upon cloth of appropriate width, and length, and cloth and pattern parts cut out together, along the pattern 45 outlines, the set of parts to form the garment will be ready to be joined with the warp threads substantially parallel one to another in all parts when so joined, substantially as described. 50

6. The product of the herein described process, being an assembled paper pattern for garments printed on a sheet of paper having longitudinal lines parallel to the marginal edges of the paper with the parts 55 of said pattern so arranged relative to said lines that when the entire pattern sheet is laid upon a bolt of cloth with the marginal edges of the bolt parallel to the longitudinal lines on the pattern, the cloth cut according to the pattern and the parts joined to form a garment, the warp threads of the cloth will run symmetrically and concurrently throughout said garment. 60

FRANK KOEWING.
